UNITED STATES PATENT OFFICE.

VICTOR GUINZBURG, OF NEW YORK, N. Y., ASSIGNOR TO THE I. B. KLEINERT RUBBER COMPANY, OF SAME PLACE.

DESIGN FOR A COLLAR AND BACK SHIELD.

SPECIFICATION forming part of Design No. 27,810, dated November 2, 1897.

Application filed June 30, 1897. Serial No. 643,035. Term of patent 14 years.

To all whom it may concern:

Be it known that I, VICTOR GUINZBURG, a citizen of the United States, residing at New York city, in the county of New York and State of New York, have invented and produced a new and original Design for a Combined Collar and Back Shield, of which the following is a specification, reference being had to the accompanying drawings.

10 Figure 1 is a perspective view of a collar and back shield, showing my design when in use. Fig. 2 is a plan of the same with the parts laid flat.

As shown in the drawings, the leading feature of my design consists of a back piece tapering from the top downward and terminating at the bottom in a narrow round end. Above the broader part of the back is a narrow strip, from which extend two flaps.

Referring now to the details of the drawings 20 by letters, A is the back of the shield. B is the collar, formed mainly by the flaps C, which collar is connected to the back by a neck D, as clearly shown in Fig. 2.

What I claim as new is—
25 The design for a combined collar and back shield substantially as herein shown and described.

In testimony whereof I affix my signature, in the presence of two witnesses, this 28th day 30 of June, 1897.

VICTOR GUINZBURG.

Witnesses:
